DECORATIVE CANDLE AND METHOD OF MAKING THE SAME

Filed May 31, 1927

Inventor:
Dawers O. C. Deckert,
by Rippy & Lingland.
His Attorneys.

UNITED STATES PATENT OFFICE.

DANVERS O. C. DECKERT, OF UNIVERSITY CITY, MISSOURI.

DECORATIVE CANDLE AND METHOD OF MAKING THE SAME.

Application filed May 31, 1927. Serial No. 195,264.

This invention relates to decorative candles, and the method of making the same.

One object of the invention is to provide an improved decorative candle having a 5 dowel rod imbedded axially therein, and having an improved connection with a wick which extends beyond the end of the candle.

Another object of the invention is to provide a decorative candle comprising improved means for obtaining sufficient rigidity to prevent the candle from bending from the desired shape in warm weather, or under 10 the influence of heat.

Another object of the invention is to provide an improved method of making the decorative candle herein disclosed.

Other objects of the invention will appear from the following description, reference being made to the accompanying drawing in 20 which

Fig. 1 is an elevation of the weighted dowel rod used in making my improved decorative candle, the wick end being in section.

Fig. 2 is a side elevation of the candle before the end thereof which imbeds the dowel weight has been cut off, the wick end of the candle being in section.

Fig. 3 is a side elevation of the finished candle.

Fig. 4 is a view of the lower end of the candle after it has been cut to remove the weight of the imbedded dowel rod and before being finished with a coat of wax.

Fig. 5 is a similar view after the finishing 30 coat of wax has been applied.

In practicing the invention to obtain my improved candle, I take a dowel rod 1 preferably of wood, though other materials may be used if desired, and form in the tapered 40 end 2 thereof a longitudinal bore 3 having an enlarged opening 4 to one side of the dowel rod. Through this bore 3 and opening 4 a wick 5 is extended, the same having a knot 6 thereon seated in the opening 4 but too large 45 to pass through the bore 3. In event the rod is composed of wood, or other relatively light material, I may attach to the end of the dowel rod opposite from the wick 5 a weight 7 which, as shown, is rolled around and clamped upon the end of the dowel rod. If 50 the dowel rod be composed of wood or other similar material it is boiled in a substance, so that when dipped in the molten wax better results will be obtained and the formation

of air bubbles avoided. An appropriate substance for this purpose comprises a mixture composed of about ninety per cent paraffine and ten per cent stearic acid. When thus treated, the weight is not essential, although it may also be used on the treated rods. I 55 have practiced the invention successfully by treating the rods in the boiling substance and then dipping the rods in the molten wax without the weights.

After having been formed and treated in 60 the manner described the dowel rod is repeatedly dipped in and withdrawn from the molten wax until a tapered candle body 8 is formed, completely imbedding said dowel rod 1 and the weight 7.

After the wax solidifies the candle body and the dowel rod are cut transversely above the upper end of the weight 7 and the lower end of the candle body is given a tapered formation, as shown in Fig. 3. Thus the 70 lower end of the dowel rod is exposed (Fig. 4). The candle is completed by applying a coating or layer of wax to the lower end of the candle body and dowel rod to conceal the latter (Fig. 5).

In the dipping operations the wick 5 may be utilized to suspend the dowel rod and, after the candle is finished, the wick may be cut to the desired length.

It will be obvious that the dowel rod may 80 be placed in a mold and the candle formed by pouring molten wax into the mold and around the dowel rod, and thereafter treating the candle to obtain the finished product as above described.

I claim:

1. A candle comprising a body of wax or the like, an elongated dowel rod completely imbedded axially in a body of wax or the like and having a longitudinal hole in its upper end opening laterally to one side of said dowel rod, and a wick extending downwardly and laterally through said hole.

2. A candle comprising a body of wax or the like, an elongated dowel rod completely 100 imbedded axially in a body of wax or the like and having a longitudinal hole in its upper end opening laterally to one side of said dowel rod, a wick extending downwardly and laterally through said hole, and means 105 for preventing the wick from being withdrawn outwardly through said hole.

3. The method of making a candle which

consists in successively dipping into molten wax and withdrawing therefrom a dowel rod having its lower end weighted so that it will sink readily into the molten wax.

5. The method of making a candle which consists in successively dipping into molten wax and withdrawing therefrom a dowel rod

having its lower end weighted so that it will sink readily into the molten wax, and then cutting the candle and the dowel rod transversely above the weighted end of the dowel rod, and applying a coating of wax to the cut end of the dowel rod.

10

DANVERS O. C. DECKERT.
